SCAFFOLD BRACKETS

D. Frank Dakin, Mount Kisco, N.Y.

Application June 26, 1957, Serial No. 668,240

3 Claims. (Cl. 248—238)

This invention relates to brackets for use with ladders in construction and repair work and particularly to brackets designed for attachment to ladders for supporting scaffold planks.

Scaffolds are commonly supported on ladders disposed in slanted position and when so disposed the bracket must be so designed as to hold the scaffold horizontal.

However, if the ladder is supported in vertical position, as by hooks or supporting rods connected to the cornice or roof, room is provided between the ladder and building wall for the scaffold bracket, or the scaffold bracket can be secured outside of the ladder instead of between the ladder and the wall, provided the ladder is properly and firmly held in position.

This invention has for its salient object to provide a scaffold bracket and means for connecting the bracket to a ladder, so designed that the same bracket and same ladder clamps or connection can be used whether the ladder is disposed in vertical or slanted position.

Another object of the invention is to provide a scaffold bracket that is so constructed that it can be made from standard tubular members or pipe and a bracket that is simple and practical in construction and can be economically manufactured and fabricated.

Further objects of the invention will appear from the following specification taken in connection with the drawings which form a part of this application, and in which—

Fig. 1 is an elevational view showing the bracket secured to a ladder disposed in slanted position;

Fig. 2 is a sectional elevation taken substantially on line 2—2 of Fig. 1, looking in the direction of the arrows;

Fig. 3 is a sectional elevation taken substantially on line 3—3 of Fig. 1, looking in the direction of the arrows;

Fig. 4 is a plan view showing the manner of connecting the outer ends of the bracket members to washers which are mounted on a vertical supporting member or pipe section;

Fig. 5 is an enlarged sectional elevation on the outer ends of the upper and lower bracket members showing the manner in which these members are mounted on the pipe at the outer ends thereof;

Fig. 6 is a top plan view of the bracket and ladder shown in Fig. 1 but showing the bracket without the scaffold planks mounted thereon;

Fig. 7 is a view similar to Fig. 6 but showing the scaffold planks in position; and

Fig. 8 is a fragmentary view similar to Fig. 1 but showing the upper bracket member with the clamp for securing the member to the ladder in a reverse position from that shown in Fig. 1 and secured to a vertical ladder instead of to a slanted ladder.

In the particular embodiment of the invention illustrated, the ladder shown in Fig. 1 and in Figs. 6 and 7 is mounted in slanted position, the upper end of the ladder being supported in any suitable manner, as against the wall of a building. The ladder has upright rails 10 and 11 and cross rungs 13.

The bracket comprises a pair of upper pipe sections or members 14 and 15 and a pair of lower pipe sections or members 16 and 17. The members 14 and 16 and 15 and 17 are connected together by struts or bracing members 19 and 20.

At their front ends the members 14 and 15 are secured to washers 25 and 26 and the lower members 16 and 17 are also secured at their front ends to washers 27 and 28. These washers are pivotally mounted on a vertical tubular member or pipe 30 and are secured in position by nuts 31, 32, 33 and 34 which are threaded on the threaded outer surface of the pipe 30.

The rear ends of the pipes 14 and 15 are threaded internally, as shown at 35, and into these threaded ends are adjustably mounted angular or hook-shaped members 36, 36. In Figs. 1 to 7 inclusive, the downwardly extending portions of the members 36 have mounted thereon clamps or connecting members which connect the upper ends of the bracket to the ladder. Each of these clamps or connecting members comprises a bar 40 having a loop-shaped portion 41 which is mounted on the downwardly extending portion 42 of the hook-shaped member 36. The rearwardly extending bar 40 has secured thereto a bar 45 which has formed on the rear end thereof a channel-shaped portion 46 adapted to embrace the rear portion of the ladder rail 10. A nut 43 is mounted on the end of portion 42 of member 36.

The bar 40 has formed therein grooves 47 and 48 and corresponding grooves are formed in the bar 45. As shown in Figs. 1 and 2, the channel portion 46 embraces the rear portion of the ladder rail 10 and the rung 13 of the ladder engages the grooves on the under surfaces of the bars 40 and 45.

The lower bracket members or pipes 16 and 17 are correspondingly threaded at their rear ends, as shown in Fig. 3, and hook-shaped members 50, similar to the members 36, are adjustably mounted in the threaded inner surfaces 51 of the members 16 and 17.

As shown in Figs. 1 and 3, the bar 45 is reversed from the position shown in Fig. 2 and the channel portion 46 embraces the front of the ladder rail 10 or 11, as the case may be.

From the foregoing description it will be noted that the scaffold bracket, when mounted as shown in Figs. 1 to 7 inclusive, will be firmly supported on the slanted ladder and that the pipes or bracket members 14 and 15 are disposed in horizontal position so as to form a firm support for the scaffold planks P.

As shown in Fig. 5, an upright member or pipe 55 is mounted in the tubular member 30 and extends upwardly therefrom. On the upper end of the pipe 55 there is shown a loop or support 56 for supporting a guard rail 57. There is also shown opposite the guard rail support 56, a right angle supporting member 58 in which the guard rail may be supported, if desired.

As hereinbefore stated, it is sometimes desirable to support the ladder in vertical position, in which case the upper end of the ladder will be connected by hooks, rods or other desirable connecting means to the roof or cornice or other part of the building on which the scaffold is to be used. In order to mount the bracket in such a manner that the scaffold will be supported in horizontal position, the hook members 36 and 50 are inverted so that the ends of the hook-shaped members 36 and 50 which extend downwardly in Fig. 1 will extend upwardly, as shown in Fig. 8. When this has been done, the clamp portion 46 of the bracket at the top of the scaffold supporting bracket will be reversed from the position shown in Fig. 3 to the position shown in Fig. 2 and will thus embrace the back of the ladder rail. Also, the clamps on the bracket members 14 and 15 which are now disposed at the bottom of the bracket will be reversed

so as to engage the front of the ladder rail instead of the back of the ladder rail.

From the foregoing description it will be clear that the same clamping brackets are used to secure the scaffold bracket to the ladder whether the clamping member embraces the rear edge of the ladder rail or the front edge thereof. This is made possible by pivoting the bars 40 and 45 on a central pin or bolt 60. Non-positive resilient holding means may be provided to hold the bars in their adjusted positions or, if desired, the pivotal member 60 may be threaded and have a nut to tighten the members in adjusted position. Furthermore, by proper adjustment and properly positioning the scaffold bracket, the same scaffold bracket and same ladder connecting means can be used to support a scaffold on a slanting ladder or a vertical ladder.

If desired, when the bracket is to be used with a vertical ladder, instead of inverting the hooked members 36 as shown in Fig. 8, the bracket itself can be inverted from the position shown in Fig. 1 and the clamps can be placed above the rungs.

Although one specific embodiment of the invention has been particularly shown and described, it will be understood that the invention is capable of modification and that changes in the construction and in the arrangement of the various cooperating parts may be made without departing from the spirit or scope of the invention, as expressed in the following claims.

What I claim is:

1. A scaffold supporting bracket for use on ladders comprising a pair of frame members converging from their rear ends toward their front ends and at their front ends being connected to a common upright post, each frame member comprising an upper member and a lower member and struts rigidly connecting said upper and lower members, the lower member being inclined upwardly toward the upper member from the rear to the front ends of the members with the front ends of all four members in vertical alinement for the mounting of a post, the rear ends of the frame members being spaced apart, and clamps comprising ladder rail embracing por-

30 tions secured to the rear ends of the upper and lower members of the frame members.

2. A scaffold supporting bracket for use on ladders comprising a pair of frame members converging from their rear ends toward their front ends and at their front ends being pivotally connected to a common upright post, each frame member comprising an upper member and a lower member and struts rigidly connecting said upper and lower members, the lower member being inclined upwardly toward the upper member from the rear to the front ends of the members with the front ends of all four members in vertical alinement for the mounting of a post, the rear ends of the frame members being spaced apart, and clamps comprising ladder rail embracing portions secured to the rear ends of the upper and lower members of the frame members.

3. A scaffold supporting bracket for use on ladders comprising a pair of frame members converging from their rear ends toward their front ends and at their front ends being connected to a common upright post, each frame member comprising an upper member and a lower member and struts rigidly connecting said upper and lower members, the lower member being inclined upwardly toward the upper member from the rear to the front ends of the members with the front ends of all four members in vertical alinement for the mounting of a post, the rear ends of the frame members being spaced apart, and clamps comprising ladder rail embracing portions secured to the rear ends of the upper and lower members of the frame members, said embracing portions of the clamps being reversible to embrace the back or front of the ladder rails.
